UNITED STATES PATENT OFFICE.

WILLIAM PETERSON, OF BROOKLYN, NEW YORK, ASSIGNOR TO INTERTYPE CORPORATION, OF BROOKLYN, NEW YORK, A CORPORATION OF NEW YORK.

SAFETY STOP MEANS FOR TYPOGRAPHICAL MACHINES.

Application filed December 23, 1927. Serial No. 242,187.

The present invention relates to improvements in typographical machines and more especially to those of the general class shown and described in Letters Patent No. 436,532 granted September 16, 1890 to O. Mergenthaler, wherein character bearing matrices are assembled and composed into a line which is then lowered by a so-called elevator to a position in front of a mold, whereupon a type bar or slug is cast in the mold and against the character-bearing edges of the matrices forming the line.

Developments of machines of this class have brought into use molds having recessed mold caps whereby type bars bearing much higher or larger characters than obtainable with the standard or usual slot-like molds are produced, and usually such recessed molds are mounted on the same mold wheel with the ordinary or standard molds, so that the operator may easily and quickly bring a recessed mold into position for use whenever such is desired.

However, when the machine is operating to cast type bars from a recessed mold of the class referred to, the line of matrices is presented to the mold at a higher level than that at which the matrix line is presented to the usual or standard mold, in order that the elevator carrying the matrix line may clear the relatively higher recessed mold cap and for other reasons, and while the machines have been provided with devices for stopping the descent of the elevator at the relatively higher level for casting from the recessed mold and with means for automatically stopping the operation of the machine in the event the elevator, for any reason does not descend sufficiently to reach such casting level, the setting of such elevator stopping devices depended on the manual manipulation thereof by the operator, and if, as sometimes occurs, the operator fails to set the stopping devices to arrest the descent of the elevator at the relatively higher level for casting from the recessed mold, after the machine has been otherwise changed to cast from the recessed mold instead of the standard mold, the elevator would descend too far and the elevator would then be in a position where it would be struck by the enlarged recessed cap of the mold as the latter advances to make the cast, and damage would result to the machine.

The present invention provides means

which is brought automatically into condition for operation when a recessed mold is brought into position for use in the machine, and which is operative automatically to stop the operation of the machine in the event the elevator stopping devices have not been set to arrest the descent of the elevator at the appropriate level for casting from the recessed mold, thereby avoiding damage which would result if the elevator were permitted to descend below such level and the operation of the machine were permitted to continue.

To these and other ends, the invention consists in certain improvements and combinations and arrangements of parts all as will be hereinafter described, the features of novelty being pointed out particularly in the claims at the end of the specification.

In the accompanying drawings:—
Fig. 1 represents a vertical section taken in a plane extending forwardly and rearwardly through the mold wheel, matrix elevator, vise cap and related parts of a typographical machine to which the present invention is applied;

Fig. 2 represents a front elevation of the mold wheel of the machine equipped with a controlling member employed in carrying out the present invention;

Fig. 3 is a perspective view of a portion of the vise cap of the machine to which is applied the automatic stopping device embodying the present invention, the stopping device in this figure being held inactive by the proper setting of the elevator stopping device for the enlarged or recessed molds; and

Fig. 4 is a view similar to Fig. 3, the stopping device of the present invention however being shown in position to stop the operation of the machine as would result from failure to properly set the elevator stopping device to conform with the rise of the enlarged or recessed mold.

Similar parts are designated by the same reference characters in the different figures.

The invention is shown in the accompanying drawings and will be hereinafter described as applied to a typographical machine of the general class disclosed in the patent hereinbefore referred to, and furthermore, the preferred embodiment of the invention is herein shown and described. The invention however might be applied to machines of types other than that referred to, and con-

structions equivalent to that herein shown and described may be used, and such will be included within the scope of the claims.

In the present instance, 1 represents a portion of the vise frame which is usually pivoted at its lower end to the front of the main frame of the machine and is provided at its upper end with a vise cap 2 which carries the usual vise jaws between which the line of 10 matrices is lowered and clamped when in casting position, as is well understood by those skilled in the art. 3 represents the so called first elevator which, in machines of this class, is slidably vertically at the front of the vise frame 1 and is provided with a head 4 which is shaped to overlie the vise cap, and the elevator head is provided with opposed jaws 5 which form a channel between them to receive an assembled line of matrices and spacers, 15 the matrix at the end of a line being designated M in Fig. 1. The matrices employed in casting type bars or slugs bearing large or display type are formed with corresponding- 20 ly enlarged character-bearing faces *m* which are in intaglio at their rear edges.

The mold wheel 6, which may be like those commonly used in machines of this class, is located behind the vise frame and first elevator and it is rotatable on or with a mold 30 wheel shaft 7 to which it is secured by a nut 8, the mold wheel shaft being mounted in the mold wheel slide which is commonly used in machines of this class and is provided with means for advancing it or moving it into the 35 position shown in Fig. 1 preparatory to the casting of a type bar or slug in a mold thereon and for retracting the mold wheel or moving it toward the right in Fig. 1 to disengage the mold from the matrix line and to permit the 40 latter to be lifted out of casting position by the elevator. The construction and operation of the mold wheel slide and its actuating mechanism is well known in machines of this class.

45 It is usual to mount on the face of the mold wheel one or more of the standard or slot-like molds 9, two of such molds being shown in the present instance, and to also mount on the face of the mold wheel one or more molds 10 50 the caps of which are recessed to form enlarged cavities so that the type bars cast therein will bear character faces which are much higher or larger than those cast in the usual or standard molds. The enlarging of the 55 mold cavities of the recessed molds 10 causes portions of the caps of these molds to extend further toward the periphery of the mold wheel than the caps of the standard molds. The periphery of the mold wheel, in machines 60 of this class, is provided with gear teeth to cooperate with a pinion which, during the operation of the machine, rotates the mold wheel from casting position, after a type bar has been cast therein, to a position where 65 the type bar or slug is ejected from the mold

by an ejector, after which the mold wheel is rotated to return the mold in use to casting position, and the pinion which engages the mold wheel also serves as means for rotating the mold wheel manually to bring another 70 or a different mold into position for operation, when such a change is desired.

Each mold body is provided usually with lower and upper rails 11 and 12 respectively on which the lower rear lugs on the matrices rest and are alined during the casting operation. In making casts in the standard molds from matrices having characters arranged at different elevations thereon, the lower rear lugs of such matrices are alined 75 on the lower or upper rail, according to whether the upper or lower characters thereon are in use, and in casting type bars from the recessed mold, the lower rear lugs on the matrices in the matrix line are alined on the 80 upper rail 12 in order that these matrices may be positioned sufficiently high to enable their upper rear lugs and the rear elevator jaw which engages them to overlie and clear the recessed or enlarged cap of such mold.

90 The control of the descent of the elevator whereby it may descend to its lowermost position so that the lower rear lugs of the matrices in the matrix line carried by it will rest on the lower rails 11 or its descent will be arrested at a relatively higher or upper level 95 so that the lower rear lugs of the matrices in the matrix line will rest on the upper rail 12, is effected by an adjustable stop or set screw 13 which extends downwardly through the 100 head of the elevator and is adapted to come to rest at its lower end on a controlling member 14 which is shown in the form of a bar which is slidable in a groove or recess 14^a 105 formed in the top of the vise cap 2, the lower end of the set screw 13 being arranged to bear directly on the upper surface of the bar 14 when the latter is set to allow the elevator to make its full descent; and when the bar 14 is shifted longitudinally to bring an upwardly extending pin or projection 15 thereon into position directly beneath the set screw 13, the descent of the elevator will be arrested at the relatively higher or upper level 110 at which the lower rear lugs on the matrices of the line carried by the elevator will be in a position to engage the upper rails 12 on the mold body. In adjusting the mold wheel for the use of a standard mold or a recessed mold, the bar 14 requires corresponding manual 115 setting by the operator whereby the descent of the elevator will be arrested at a level conforming with the mold thus brought into use.

120 Means is employed for stopping the operation of the machine in the event the elevator fails to descend fully to the level conforming with the setting of the stop bar 14, as for example might occur if the matrix line 125 is of an excess length to enter between the 130

vise jaws. Such means, as commonly used for this purpose, comprises a stop rod 16 which is guided to move forwardly and rearwardly and also vertically by a pin 17 which is fixed to a part 18 of the stationary frame of the machine, the stop rod being yieldingly pressed upwardly by a spring 19. The lower end of the stop rod rests against a bar or lever 20 which forms part of the main clutch disengaging or stop mechanism of the machine, as will be understood from the patent hereinbefore referred to. The stop rod is provided at its rear side with a blade 21 which, when the stop rod is in its fully lowered position corresponding with a full descent of the elevator, will be slightly below the level of a dog or plunger 22 which is slidably mounted in the stationary frame 18 and is pushed forwardly by the engagement of a mold on the mold wheel against its rear end, when the mold wheel advances to casting position, the stop mechanism being then unaffected; but if the stop rod is not fully lowered, as would be the case if the elevator does not descend fully to its appropriate level, the blade 21 will be in the path of the forward end of the dog 22, and when this dog is pushed forwardly by the advance of the mold wheel, the stop rod 16 will, in consequence, be pushed forwardly, thereby causing it to actuate the bar or lever 20 of the stop mechanism and thereby automatically stop the operation of the machine. The stop rod 16 is pushed downwardly each time the elevator approaches the limit of its descent, the upper end 23 of the stop rod projecting upwardly through the vise cap 2 to a position above the latter so that it may be actuated by a filling-in piece 24 which is pivotally or movably attached to the bar 14. This filling-in piece is formed with lower and upper steps 25 and 26, one or the other of which is brought into position directly beneath a set screw 27 which projects downwardly through the head of the elevator, according to the setting of the bar 14. Thus, when the bar 14 occupies its normal position so that the set screw or stop 13 will come to rest directly on the top surface of the bar 14, the lower end of the set screw 27 will engage the lower step 25 of the filling-in piece, and the final portion of the descent of the elevator to its lowermost position will cause the stop rod 16 to be forced downwardly far enough to carry the blade 21 thereon out of the path of the dog 22, so that the operation of the machine will not be stopped; and when the bar 14 is shifted into the position shown in Fig. 3 to arrest the matrix line at the relatively higher level for the casting of type bars in a recessed mold which has been brought into use, the lower end of the set screw 27 will engage the upper step 26 of the filling-in piece while the set screw 13 will be aligned with the pin or projection 15 on the bar 14, and as the elevator completes its descent to the relatively higher level, the set screw 27, acting through the filling-in piece 24, will force the stop rod 16 downwardly until the blade 21 thereon is out of the path of the dog 22, so that the operation of the machine will not be stopped.

However, it sometimes occurs that the operator of the machine brings a recessed mold into position for use but fails to shift the stop bar 14 from its normal position, shown, for example, Fig. 4, to the appropriate position shown in Fig. 3, and if the machine is operated in that condition, the bar 14 would not stop the descent of the elevator until it reached its lowermost position, and the stop mechanism would fail to stop the machine as the set screw 27 would engage the lower step 25 of the filling-in piece and the latter would be free to act to depress the stop rod 16 in the normal way. If the machine operated in that condition, the cap of the recessed mold would come against the unduly lowered rear jaw of the elevator, during the advance of the mold wheel to casting position, and the resulting obstruction to the movement of the mold wheel would cause damage to the machine.

The present invention provides means which is automatically brought into condition for operation when a recessed mold is brought into condition for use and which is operative automatically to stop the operation of the machine in the event the operator fails to set the stop bar 14 in proper position to arrest the descent of the elevator at the upper level for the making of a cast from a recessed mold. This device, as shown in the present instance, comprises a bracket 28 a portion of which overlies the vise cap and is fixed thereto by screws 29 and 30, an extension of this bracket forming an arm 31 which is arranged beneath the vise cap, and a lever 32 which preferably rests on the bracket 28 and is pivoted on the screw 30 which may be shouldered for this purpose. The lever has an arm 33 the extremity of which is off-set downwardly so that it occupies a position on or immediately above the top surface of the vise cap, and this arm has a pin or projection 34 which extends upwardly therefrom. The arm 33 is of such length and position that swing of the lever 32 about the pivot screw 30 will carry the pin or projection 34 into or out of a position beneath the filler block 24. Excessive movement of the lever 32 is prevented by the head of the screw 29 which is arranged in a recess of appropriate size in the lever 32. The lever 32 is formed with a heel 35 the rear edge of which extends substantially longitudinally of the stop bar 14 and overlies said bar, and a pin or projection 36 is fixed on the upper side of the bar 14 so that when the bar

14 occupies the position shown in Fig. 3, the pin will bear against the rear edge of the heel 35 and will thus hold the projection 34 out of position beneath the filling-in piece 24, and when the bar 14 occupies the position shown in Fig. 4, the pin will be opposite to a cut-away portion 37 adjacent to the heel 35 of the lever, and the latter is then free to swing in a direction which will carry the 10 projection 34 thereon beneath the filling-in piece 24. The bar 14 is shown in Fig. 4 in position to permit the elevator to descend to its lowermost level, and when the projection 34 is swung into position beneath the filling-in piece 24, as shown in Fig. 4, descent of the filling-in piece will be prevented by the interposition of the projection 34 between it and the top of the vise cap so that should the elevator attempt to descend to its lowermost 20 level, the stop bar 16 will not be pushed down so as to remove the blade 21 thereon from the path of the dog 22, and the advance of the mold wheel would then actuate the bar or lever 20 to stop the operation of the machine. 25 Means is provided for automatically swinging the lever 32 to bring the projection 34 thereon beneath the filling-in piece 24 and thus stop the operation of the machine in the event the stop bar 14 has not been properly 30 set to conform with the use of a recessed mold. Such means consists preferably of a lever 38 the upper end of which is formed with a hub 39 which fits loosely on a screw or other suitable pivot 40 which is fixed to the forward side of the bracket 28, the loose fit of the hub 39 on the screw allowing the lever 38 to rock in a forward and rearward direction as well as to rotate about the screw or pivot 35 as an axis. A spring 41 is provided which 40 yieldingly holds the lever 38 in its rearward position but will allow the lever to move forwardly, a coil spring being preferably used which is interposed between the hub 38 of the lever and the hub of the screw or pivot 45 40. A flat spring 42 is fixed to the lever 38 so that it projects upwardly therefrom radially of the pivot screw 40, and the upper end of this spring rests in a slot 43 which extends forwardly and to the front edge of the lever 50 32. The lower end of the lever 38 extends beneath the vise cap and its extremity is provided with a bar or blade 44 which is adapted to be engaged by the forward face of the mold wheel when the latter advances preparatory to a casting operation. The mold 55 wheel is provided with means corresponding with a recessed mold thereon, such means being operative, when a recessed mold is brought into position for use, to act on the bar or blade 44 of the lever 38 to rotate the lever 38 and thereby cause the spring 42 to swing the lever 32 into active position. Such means consists preferably of a lug 45 which 60 is positioned on the forward face of the mold wheel diametrically opposite to each recessed

mold thereon, the lug being preferably shaped to fit against the mold wheel securing nut 8 and being held in place by a screw 46 which is accommodated in the usual space 8^a which surrounds the nut 8, an eccentric or cam screw being preferably used the eccentric body of which is arranged to bear against a flat side of the nut 8 while a flange 45^a on the lug 45 abuts against the shoulder which surrounds the recess 8^a, rotation of the screw serving to lock the lug firmly and adjustably in place. The stem 47 of the screw extends rotatably through the lug 45 and it is threaded on its forward end to receive a jam nut 48 whereby the screw may be locked in 70 adjusted position. It will be understood that one of these lugs will be provided in a position diametrically opposite to each recessed mold on the mold wheel. The lug projects forwardly from the front face of the mold wheel and it is so positioned that when the mold wheel rotates to bring a recessed mold into casting position, this lug will engage the upper edge of the bar or blade 44 on the lever 38 and will cause the lever 38 to swing about the screw 40 as a pivot, thus moving the spring 42 toward the right in Figs. 3 and 4. If the stop bar 14 has been properly set to 80 arrest the descent of the elevator at the proper level for the recessed mold, the heel 35 will merely bank against the pin 36 on the bar 14, and the lever 32 is held from swinging about its pivot 30 to carry the projection 34 beneath the filling-in piece 24, and hence the machine will be permitted to 90 operate, the stop rod 16 being depressed into non-operative or non-stopping position upon each descent of the elevator, through the action of the screw 27 on the elevator which depresses the filling-in piece 24, the latter being 95 then free to descend and move the stopping rod 16 into non-stopping position. However, if a recessed mold is brought into position for use and it is attempted to operate the machine without correspondingly setting the 100 stop bar 14, the rotative movement of the spring 42 will cause the lever 32 to swing about its pivot 30 and to carry the projection 34 into position beneath the filling-in piece 24, as the pin 36 on the bar 14, while the latter 105 is in its normal position as shown in Fig. 4, will be opposite to the cut-away portion 37 of the lever 32 and hence will not restrain movement thereof under the action of the spring 42. If it is attempted to operate the 110 machine under these conditions, the movement of the elevator, as it approaches its lowermost position, will be arrested by the contact of the screw 27 thereon with the filling-in piece 24 and depression of the filling-in piece will be prevented by the projection 34 which will then be interposed between it and the top of the vise cap, in consequence 115 of which the stop rod 16 will remain in its elevated position so that the blade 21 thereon 120

130

is in the path of the dog 22, and the advance of the mold wheel will cause the dog 22 to engage the blade 21 and thereby shift the stop rod 16 forwardly, the member 20 of the stop mechanism being then actuated to stop the machine. Damage to the machine, due to abnormal low position of the elevator which would bring the rear jaw 15 thereon into a position to be struck by the cap of the recessed mold when the mold wheel advances for a cast, is thereby avoided.

During the normal operations of the machine, the bar or blade 44 on the lever 38 will be engaged by the front of the mold wheel 15 and the advance of the latter preparatory to each casting operation will push the lower end of the lever forwardly, but these forward and rearward movements of the lever 38 under normal operation conditions will 20 be idle and they are permitted by the loose fit of the hub 39 on the screw or pivot 40 and the slot engagement between the spring 42 and the lever 32. Also, the flexibility of the spring 42 in the direction of rotation of 25 the arm 38 will allow the lever 32 to remain immovable while the lever 38 is swung by the lug 45, when the bar 14 is properly set for a recessed mold, in which event the pin 36 thereon will engage the heel 35 and thus 30 block rotation of the lever 32. The lower end of the lever 38 is yieldingly drawn in an upward and rearward direction by a tension spring 47^a which is attached at one end to 35 said lever and at its other end to the lower arm 31 of the bracket 28, the bar or blade 44 on the lever 38 being thus held in a position to be engaged by the forward face of the advancing mold wheel and by the lower side of the lug 45 thereon.

40 While the lug 45 for each recessed mold will act, in the manner just described, to stop the machine in the event it is attempted to operate it with a recessed mold in position for use but without proper setting of the elevator stop bar 14, the stopping means of 45 the present invention will not interfere with the usual operations of the machine in making casts from the standard molds, as there are no lugs opposite to the standard molds 50 to actuate lever 32 and hence the latter will remain inactive while the machine is operating with a standard mold in use.

I claim as my invention:—

1. In a machine of the class described comprising an elevator for conducting lines of matrices to different casting levels and means capable of being set manually to stop the elevator at the different casting levels, a mold adapted to cooperate with the elevator at one 55 of said levels only, and means positioned by the bringing of said mold into casting position, to stop the elevator in the event the elevator stopping means is set to stop the elevator at a level other than that at which said 60 mold is adapted to cooperate with it.

2. In a machine of the class described having an elevator for conducting lines of matrices to casting position, and means capable of being set to stop the elevator at different casting levels, a mold capable of cooperating 70 with the elevator at one only of said levels, and a device having means to render it operative automatically by the movement of said mold into position for use for stopping the machine in the event the elevator stopping 75 means is set to stop the elevator at a level other than that at which said mold is capable of cooperating with it.

3. In a machine of the class described having an elevator for conducting lines of matrices to casting position, and means for stopping the elevator at different casting levels, a mold adapted to cooperate with the elevator at one of said levels only and stopping means 80 for the machine including a member movable with said mold for automatically stopping the machine in the event the elevator stopping means is set to stop the elevator at a level other than that at which said mold is adapted 85 to cooperate with it.

4. In a machine of the class described comprising an elevator for conducting lines of matrices to casting position, elevator stopping means capable of being set in different positions to stop the elevator at different 90 levels, and stopping means for the machine which is controlled by the elevator stopping means and is rendered inactive when the elevator assumes the level for which the elevator stopping means is set, a mold adapted to 95 cooperate with the elevator at one of said levels only, and means operative, when said mold is in position for use, to cause the machine stopping means to act to stop the machine in the event the elevator stopping means is set to stop the elevator at a level other than that at which the mold is adapted 100 to cooperate with it.

5. In a machine of the class described having an elevator for conducting lines of matrices to casting position, a stop member capable of being set in different positions to stop the elevator at different casting levels, and stopping means for the machine controlled by the elevator stop member, a mold 110 adapted to cooperate with the elevator at one of said casting levels, and means which is rendered active, when said mold is brought into use, to cause the stopping means to stop the machine in the event said stop member is 115 set to stop the elevator at a level other than that at which said mold is adapted to cooperate with it.

6. In a machine of the class described having an elevator for conducting lines of matrices, and a stop member for stopping the elevator at different levels, a mold adapted to cooperate with the elevator at one of said levels only, and stopping means for the machine including an element which is rendered 125 130

operative when said stopping member is set to stop the elevator at a level other than that at which said mold is adapted to cooperate with it, and a member associated with said 5 mold and movable into position when said mold is brought into position for use, to actuate said element to cause operation of the machine stopping means.

7. In a machine of the class described having an elevator for lowering lines of matrices to casting position, a stop member capable of being set in different positions to stop the elevator at different casting levels, stopping means for the machine, and a part movable in 10 to different set positions in unison with said stop member and operative to render the machine stopping means inactive, a mold adapted to cooperate with the elevator at one of its casting levels, an element controlled by said 15 stop member and movable into a position to prevent operation of said part when the stop member is set to stop the elevator at a level other than that at which said mold is adapted to cooperate with it, and means associated 20 with said mold and movable into position, when the latter is brought into position for use, to cause movement of said element into position to prevent operation of said part and thereby permit operation of the machine 25 stopping means.

8. In a machine of the class described having an elevator for lowering lines of matrices to casting position, a stop member capable of being set to stop the descent of the elevator at one or another casting level, stopping means for the machine, and a part carried by said elevator stop member and movable by the elevator to render the machine stopping means inactive, a mold adapted to 30 operate with the elevator at one of said casting levels, an element controlled by the setting of said stop member and movable into a position to prevent operation of said part by the elevator when said stop member is set to stop 35 the elevator at a level other than that at which said mold is adapted to cooperate with it, and means rendered operative when said mold is brought into casting position for actuating 40 said element.

50 9. In a machine of the class described hav-

ing an elevator for lowering lines of matrices to casting position, a stop member capable of being set in different positions to stop the elevator at different casting levels and having a part which is set concurrently therewith and 55 arranged to be engaged and depressed by the elevator, and stopping means for the machine embodying a controlling member arranged to be depressed into inactive position when said part is depressed by the elevator, a mold 60 adapted to cooperate with the elevator at one of said casting levels, a locking member controlled by the elevator stop member and movable into a position to prevent depression of said part when the elevator stop member 65 is set to stop the elevator at a level different from that at which said mold is adapted to cooperate with it, and means located in predetermined position relatively to said mold and movable, when said mold is brought into 70 position for use, into position to move the locking member into position to prevent depression of said part.

10. In a machine of the class described having an elevator for lowering lines of matrices to casting position, a stop bar capable of being set to arrest the descent of the elevator at relatively upper and lower casting levels and carrying a filling-in piece arranged to be depressed by the elevator, and stopping means 75 for the machine including a rod arranged to be depressed by said filling-in piece and thus render the stopping means inactive; a mold adapted to cooperate with the elevator while the latter is at the relatively upper casting 80 level, a locking member which is held inactive by the elevator stop member when the latter is set to stop the elevator at the upper casting level but is movable into position to prevent depression of the filling-in piece when the 85 elevator stop member is set to stop the elevator at the lower level, a lever having means to act yieldingly on said locking member to move it into active position, and a part movable with said mold, when the latter is brought 90 into position for use, into engagement with said lever to actuate it.

In testimony whereof I have hereunto set my hand.

WILLIAM PETERSON.
